UNITED STATES PATENT OFFICE

JARRETT B. WOOD, OF TULSA, OKLAHOMA

STEAM BOILER

Application filed June 18, 1929. Serial No. 371,820.

One of the objects of my said invention is the provision of a steam boiler of high efficiency in proportion to its size.

Another object is the provision of a boiler in which steam is generated in the lower portion of the boiler, is caused to rise through a center column, is preheated enroute upward to an upper steam chamber, and is then passed to superheated coils and from the coils directly to the point of use.

Another object is the provision in a steam boiler of a peculiar and advantageous casing.

Another object is the provision of a practically advantageous coupling.

Other objects and practicable advantages of the invention will be fully understood from the following description and claims when the same are read in connection with the drawings, accompanying and forming part of this specification, in which:

Figure 1 is a sectional perspective illustrative of a preferred embodiment of my invention.

Figure 2 is an enlarged view comprising disconnected parts of the novel and advantageous couplings hereinafter explicitly described.

Figure 3 is a view partly in perspective and partly in section showing the receiver for superheated steam and certain connections appurtenant thereto.

Figure 4 is a detail perspective illustrating the lower and upper head and the steam column interposed between the same.

Figure 5 is a fragmentary perspective illustrating the foraminous upper portion of the steam column, constituting a baffle.

Similar numerals of reference designate corresponding parts in all of the views of the drawings.

Among other elements my novel boiler comprises a lower head 1, a steam column 2 and an upper head 3, the column 2 communicating with the interior of the lower head 1 and being extended through the upper head 3 to the upper wall thereof, and being provided opposite the interior of the head 3 with a baffle portion 3a in which are perforations 29 for the passage of steam from the interior of the column 2 to the in-

terior of the head 3. At 27 the lower head 1 is provided with a water inlet as shown in Figure 4, and at 4 couplings are associated with the lower wall of the upper head 3.

Superheating coils 5 are disposed in the superheating chamber 15 and are grouped about the steam column 2. The upper ends of the superheating coils 5 are attached to the lower wall of the head 3 and are put into communication with the interior of the head 3 through the medium of couplings referred to, one of which is illustrated in detail in Figure 2. The said couplings are

identical in construction and therefore a detailed description of the one in Figure 2 will suffice to impart a definite understanding of all. Said coupling 4 comprises an upper member 4a closed at its upper end and open at its lower end and exteriorly threaded at 5a and having perforations 6a, also having a lower enlarged portion 7a to form a shoulder for opposition to the lower wall of the head 3, a lower member 8a joined to the upper end of one coil 5 and having a taper seat 9a in its upper end to receive the correspondingly tapered lower end of the member 4a, and a headed bolt 10a passed upwardly through the members 8a and 4a and threaded into a socket 11a in the upper end of the member 4a.

By virtue of the construction described the upper end of the coils 5 are strongly connected to the head 3, and this in such manner that when occasion demands the coils 5 may be expeditiously and easily disconnected from the said head 3.

The lower ends of the coils 5 are preferably merged into upright portions grouped about the steam column 2, and the said upright portions are connected by unions 26 with the lower ends of pipes 6 which are carried through the upper head 3 and are connected, in turn, with a receiver for superheated steam 7, said receiver 7 being disposed above the upper head 3 and being equipped with a steam ejection pipe 9 connected by union 28 with a pipe 10 designed to lead superheated steam to an engine or other point of use. The pipe 9 is connected

to the receiver 7 through the medium of a coupling 8 which is of the same construction as the coupling 4, before described, except that the coupling 8 is inverted. Compare 5 Figures 2 and 3.

A fire box is designated by 11, and from the said fire box interior, flues 12 lead through the lower head 1 to the superheating chamber 15.

10 Flues 13 lead through the upper head 3 and effect connections between the superheating chamber 15 and the uppermost heating chamber 16 which latter has an outlet at 17 for products of combustion.

15 Long flues 14 are arranged in spaced relation in the steam column 2 and lead from the interior of the fire box 11 to the interior of the upper heating chamber 16 as will be readily discerned in Figure 1.

20 In the practical use of my novel boiler the steam is generated in the lower portion of the boiler and passes upwardly through the column 2, and consequently the steam is preheated on its way upward to the steam 25 chamber 3, this by virtue of the fact that when opposite the interior of the chamber 3 the steam encounters the foraminous baffle 3x, before described, and from the steam chamber 3 the steam passes through

30 the coils 5 where the steam is superheated, and from the said coils 5 the steam passes directly to the receiver 7, and from said receiver 7 is taken through the pipes or conduits described, to the engine or other point 35 of use. From this it follows that steam superheated in the coils 5 does not come in contact with the preheated steam.

In addition to the casing or jacket portion 18, the casing or jacket includes the 40 lid 19 flanged to the portion of the casing below it and easily removable to afford access to the upper heat chamber 16. Seated in the lid 19 is a loose cover 20.

At 21 is the chassis of the boiler, and at 45 22 is a bracket, said bracket being riveted to said chassis as illustrated.

The said bracket 22 is provided at its lower end with a flange which serves as a rest for the casing or jacket, and the said 50 bracket 22 is provided with an outwardly directed upper portion to serve as a rest over the top of the chassis 21. At 23 are tie rods connected to fittings 24 and having their lower portions passed through apertures formed in the bracket 22 and chassis 21 and threaded below the flange of the chassis to receive a nut and equipped between the nut and the chassis flange with an expansion spring designed to permit of the 55 necessary expansion and contraction. Eye bolts 25, see Figure 1, are employed for the suspension of the fire box 11 from the bracket 22.

It will be apparent from the foregoing 60 that products of combustion pass from the

fire box 11 through the flues 14 to the upper heating chamber 16, and products of combustion also pass from the fire box 11 through the flues 12, the superheating chamber 15 and the flues 13, in the order named, 70 to the upper heating chamber 16, and from said chamber 16 the products of combustion pass as before stated out through the outlet 17, Figure 1.

Any desirable burner or other heating 75 means may be employed in the fire box 11, within the purview of my invention.

I have entered into a detailed description of the construction and relative arrangement of parts embraced in the present and preferred embodiment of my invention, so as to impart a full, clear, and exact understanding of the said embodiment. I do not desire, however, to be understood as limiting myself to the construction and relative 80 arrangement of elements as illustrated, my invention being defined by my appended claims, within the scope of which modifications may be made without departure from my invention.

Having thus described the invention, what I claim as new and desire to secure by Letters Patent is:—

1. In a boiler, the combination of a lower head, an upper head spaced above the lower head, flues extending through said heads, a column in communication with the lower head and having a foraminous portion extending within the upper head and with its foraminations in communication with the interior of said upper head, flues extending through the column, a fire box in communication with the lower ends of the latter flues, an upper heating chamber in communication with the upper ends of the flues, superheating coils in a chamber between the lower and upper heads and disposed about the column and having their upper ends connected with the interior of the upper head, and a receiver located in the upper heating chamber and connected with the lower ends of the superheating coils and having a conduit for carrying steam to the point of use.

2. In a steam boiler, the combination of lower and upper spaced heads, a steam column communicating with the interior of the lower head and having a foraminous baffle portion extending within the interior of the upper head, flues extending through the lower head, flues extending through the upper head, flues extending through the lower head and the column, a casing forming in conjunction with the heads and column a superheating chamber, and superheating coils disposed in said chamber and connected at their upper ends with the upper head interior, a heating chamber above the upper head and in communication with the flues therethrough, a receiver disposed in said heating chamber and above the flues through 100

the column, said receiver in communication with the lower ends of said superheating coils, and means for conducting superheated steam from said receiver.

5 3. In a steam boiler and in combination, a fire box, a water and steam head arranged above said fire box, flues extending upwardly through said head, an upper steam head spaced above the first named head, flues
10 through said upper head, a heating chamber above said upper head, a casing portion forming with the heads and a column a superheating chamber, the said column communicating with the lower end of the lower
15 head and having a foraminous baffle portion extending within the upper head, flues extending through said column and leading from the fire box to the upper heating chamber, a receiver disposed in the upper heating
20 chamber and equipped with means for conducting steam to a point of use, and superheaters connected with said receiver and disposed in said superheating chamber and also connected with the interior of the upper
25 head.

In testimony whereof I affix my signature.
JARRETT B. WOOD.
